UNITED STATES PATENT OFFICE

ANDREW C. HANSON, OF RACINE, WISCONSIN

CONTROLLING DEVICE FOR WINDOW SHADES

Application filed February 17, 1930. Serial No. 429,106.

This invention relates to improvements in controlling devices for window shades.

It is one of the objects of the present invention to provide a fixture for one end portion of a curtain or shade roller providing for the retention of the curtain at any desired height and eliminating the need of a spring in the curtain roller.

A further object of the invention is to provide a curtain roller fixture which, when applied to the end portion of a curtain roller, will very satisfactorily balance and tension the curtain during its various movements and at any position of adjustment.

15 A further object of the invention is to provide a curtain roller fixture having friction means which is adjustable from the exterior of the fixture for holding the roller in any desired position.

20 A further object of the invention is to provide a curtain roller fixture which, when applied to a window casing, is neat and attractive in appearance and which is very simple mechanically and can be manufactured very reasonably.

25 A further object of the invention is to provide a curtain roller fixture which is of very simple construction, is strong and durable, is easily installed, and is well adapted for the purposes described.

30 With the above and other objects in view the invention consists of the improved control device for window shades, and its parts and combinations as set forth in the claims,

35 and all equivalents thereof.

35 In the accompanying drawings illustrating one complete embodiment of the preferred form of the invention, in which the same reference characters indicate the same parts in all of the views:

Fig. 1 is a front view of a window casing and window sashes equipped with a shade embodying the improved controlling device;

45 Fig. 2 is an enlarged view of the curtain roller and curtain thereon showing the curtain roller mounted at one end in a bracket of ordinary construction and mounted at its other end in the improved fixture, parts being broken away and parts being shown in

section to bring out the details of construction;

Fig. 3 is a front view of the improved curtain roller fixture shown mounted on a portion of a window casing;

Fig. 4 is an enlarged vertical sectional view of the fixture;

Fig. 5 is a sectional view taken on line 5-5 of Fig. 2; and

Fig. 6 is a broken away view showing a portion of the casing with an edge view of the improved fixture in connection therewith.

Referring now more particularly to the drawings it will appear that the numeral 8 designates a window casing having window sashes 9 slidably mounted therein. The window sashes are adapted to be covered or shaded to any desired degree by a shade or curtain 10 which is secured at its upper end

portion to and adapted to be rolled about a roller 11 mounted horizontally at the upper portion of the casing. One end portion of said roller is covered by a metal ferrule 11' of ordinary construction, and a stud 12 projecting outwardly therefrom is journaled in

70 a bracket 13 of ordinary construction which is mounted on one side of the upper portion of the window casing. The other end portion of the roller 11 carries a metal ferrule 14 of a somewhat modified construction. By

75 reference particularly to Figs. 2 and 5 it will be noted that said ferrule 14 has its outer face formed with a slot or opening 15 of rectangular shape, and the stock stamped out of

80 said face to form the opening is bent inwardly, as at 16, to extend toward the end portion of the roller 11. Said ferrule 14 is adapted for revoluble engagement with the improved

85 curtain roller fixture indicated generally by the numeral 17 which will now be described in detail.

90 Said curtain roller fixture 17 is mounted on the upper portion of the window casing 8 opposite the fixture 12. The body of said fixture 17 is cup-shaped, and extending from

95 opposed side portions of the annular wall 18 thereof are laterally extending legs or brackets 19, through which screws 20 are passed to attach said fixture to the casing 8. Seated within the cup-shaped body portion

against the inner surface of the bottom or end 21 thereof is a disc 22 having inwardly projecting portions 23 stamped therefrom and extending inwardly to form a drum. The disc 22 is revolubly mounted on the shank of a rivet 24, the latter being connected to the central portion of the end 21 of the casing.

One pair of the projecting portions 23 of the disc 22 extends outwardly a greater distance than the other pair and said projecting portions are arranged to fit into the slot or opening 15 of the ferrule 14 to form means for revolubly connecting the ferrule to the drum portion of the fixture as shown in Fig. 2.

The inner end portion of a tape or cord 25 is secured to one of the projecting portions 23 of the disc and said tape is arranged to be wound around the four projecting portions as indicated in Fig. 4. The annular side wall 18 of the fixture is provided with an opening 26 through which the tape or cord 25 extends. A curved braking strip 27 is formed at one end with a depending lug 28 which fits into an opening 29 of the casing, and at its other end with an opening 30 through which the tape is adapted to be extended so that it may depend downwardly along the side of the window casing. The braking strip 27 is bowed outwardly slightly from the side of the casing so as to normally engage the tape only at a point adjacent the opening 30. A screw 31, which extends through an opening 32 of the braking strip, is threaded into the side of the casing. By adjusting said screw, the amount of pressure placed upon the tape by the strip 27 may be varied. The extreme lower end of the tape 25 may carry a ring 33 for convenience in operating.

In use, a curtain roller is mounted in the manner shown in Figs. 1 and 2, with the elongated projecting portions 23 of the drum of the fixture extending into the opening of the end ferrule 14 of the roller. The shade may be lowered by pulling it downwardly in the ordinary manner with the ordinary shade cord, and it is retained in any adjusted position because of the frictional engagement between the braking strip 27 and the tape 25. When the curtain is lowered the tape 25 is wound upon the drum forming projecting portions 23 of the fixture, and to raise the curtain the end portion of the tape 25 is pulled downwardly, unwinding the tape from the drum and turning the drum and curtain roller in a direction to effect the rolling or winding of the shade upon the curtain roller.

As mentioned, the degree of frictional engagement between the braking strip 27 and the tape 25 may be adjusted by loosening or tightening the screw 31. For a large heavy curtain, it is desirable to have more of a frictional engagement between said parts than

when a light curtain is used. As shown in Fig. 6, the head of the screw 31 is readily accessible for adjustment purposes without disturbing the shade or fixture, thereby rendering the exterior braking means very advantageous.

From the foregoing description it will be seen that the improved controlling device for window shades is both simple in its construction and operation, and is well adapted for the purposes set forth.

What I claim is:

1. A curtain roller fixture, comprising a casing, a drum revolubly mounted therewithin and engageable with the end portion of a curtain roller, a flexible member wound on said drum and extending exteriorly thereof, operation of said flexible member serving to rotate said drum and roller to raise the curtain, and braking means positioned exteriorly of the casing and engageable with the flexible member for pressing the flexible member against a casing portion to hold the curtain in any position of adjustment.

2. A curtain roller fixture, comprising a casing, a drum revolubly mounted therewithin and engageable with the end portion of a curtain roller, a flexible member wound on said drum and extending exteriorly thereof, operation of said flexible member serving to rotate said drum and roller to raise the curtain, braking means positioned exteriorly of the casing and engageable with the flexible member for pressing the flexible member against a casing portion to hold the curtain in any position of adjustment, and means in connection with said braking means for adjusting the pressure exerted thereby on the flexible member to suit the requirements of curtains of different weights.

3. A curtain roller fixture, comprising a casing, a drum revolubly mounted therewithin and engageable with the end portion of a curtain roller, a flexible member wound on said drum and extending exteriorly thereof, operation of said flexible member serving to rotate said drum and roller to raise the curtain, and a curved braking strip positioned exteriorly of the casing for pressing the flexible member against a casing portion to hold the curtain in any position of adjustment.

4. A curtain roller fixture, comprising a casing, a drum revolubly mounted therewithin and engageable with the end portion of a curtain roller, a flexible member wound on said drum and extending exteriorly thereof, a braking strip connected to the casing at one end and having its other end engageable with the flexible member to press the latter against a casing portion, and a screw threaded into the casing and engaging the braking strip to adjust the amount of pressure of the latter upon the flexible member.

5. A curtain roller fixture, comprising a cylindrical casing having a peripheral open-

ing therein, a drum revolvably mounted therewithin and engageable with the end portion of a curtain roller, a flexible member wound on said drum and extending through the opening of the casing, and a curved braking strip connected to the exterior of the casing at one end and having an eye near its other end through which the flexible member extends, said strip being centrally bowed outwardly to clear the flexible member as it passes through the casing opening, said end of the braking strip having the eye being engageable with the flexible member to press the latter against the side of the casing for holding the curtain in any desired position of adjustment.

6. A curtain roller fixture, comprising a cylindrical casing, a drum revolvably mounted therewithin and engageable with the end portion of a curtain roller, a flexible member wound on said drum and extending exteriorly thereof, a curved braking strip connected to the curved portion of the casing and being normally bowed outwardly therefrom, said braking strip being engageable with the flexible member, and screw threaded in the casing and engageable with the bowed portion of the braking strip to adjust the amount of pressure of the latter upon the flexible member.

7. A curtain roller fixture, comprising a rotatably mounted drum engageable with the end portion of a curtain roller, a flexible member having a portion wound on said drum, operation of said flexible member serving to rotate said drum and roller to raise the curtain, and braking means engageable with an unwound portion of the flexible member to press the latter against a casing portion for holding the curtain in any desired position of adjustment.

In testimony whereof, I affix my signature.
ANDREW C. HANSON.
